ABSTRACT: A triangle sound simulating device to be employed in an electronic musical instrument is composed of a fundamental sound signal oscillator, at least one additional sound signal oscillator for generating an additional sound signal of lower frequency than that of the fundamental sound frequency, the output level of the additional sound signal being selected to be lower than the output level of the fundamental sound signal obtained from the fundamental sound signal oscillator, and a switching circuit of nonlinear characteristic which, upon reception of the output signals can create a difference frequency sound signal of a frequency equal to the difference between those of the output signals each time the switching circuit is switched.

TRIANGLE SOUND SIMULATING DEVICE

BACKGROUND OF INVENTION

This invention relates to an electronic device for simulating the sounds generated from musical triangles. In electronic musical instruments, by employing combinations of active circuit elements such as electron tubes and transistors and passive circuit elements such as resistors, capacitors, and inductors, various circuits are combined to constitute sound effect generators which simulate sounds of various kinds of natural musical instruments. Although it is comparatively easy to obtain electronic devices for simulating artificially, sounds generated from string musical instruments and wind instruments, the sounds of percussion instruments which are more complicated have not been successfully simulated with sufficient naturalness of auditory sensation.

Conventional devices for simulating percussion instruments, more specifically the sound of a triangle, have been composed of merely a single oscillator and a tone-color circuit for shaping the output of the oscillator. However, because merely a fundamental frequency and some of the higher harmonics thereof are generated from the single oscillator, the sound thus simulated by such an arrangement of the circuit is too simple and lacks naturalness in auditory sensation, although the organization thereof is simple and thereby advantageous.

SUMMARY OF THE INVENTION

Therefore, the primary object of the present invention is to provide a device for simulating the natural sound of a triangle whereby the above described drawbacks of the conventional sound simulating devices can be substantially eliminated.

Another object of the present invention is to provide a novel device for simulating the sound of a triangle which can generate a sound far closer to the natural sound of a triangle.

Still another object of the present invention is to provide a novel device for simulating the sound of a triangle which is simple in organization and can be easily produced. These and other objects of the present invention can be achieved by a novel device for simulating the sound of a triangle which comprises an oscillator for generating a fundamental sound signal, at least one additional sound oscillator for generating an additional sound signal having a lower frequency than that of the fundamental sound signal, and a switching circuit of nonlinear characteristic which can receive all of the above mentioned fundamental and additional signals simultaneously and create sound signal having frequencies equal to the differences between the frequencies of these signals, the sound level of the additional sound signal being selected to be at a lower level than that of the fundamental sound signal.

The nature, principle, and utility of the present invention will be more clearly understood from the following detailed description with reference to the accompanying drawing.

BRIEF DESCRIPTION OF DRAWING

In the drawing:

FIG. 1 is a block diagram for an explanation of the principle of the present invention; and FIG. 2 is an electric circuit diagram showing a device for simulating the sound of a triangle, which constitutes a preferred embodiment of the present invention.

DETAILED DESCRIPTION

Referring now to FIG. 1 which shows a basic concept of the present invention, the device shown comprises an oscillator 1 for generating a fundamental sound signal having a frequency f_1 , an additional sound oscillator 2 for generating an additional sound signal having a frequency f_2 lower than the frequency f_1 of the fundamental sound signal, a switching circuit 3, and a tone-color circuit 4. With the above described organization of the simulating device of a triangle sound, the output of the fundamental sound oscillator 1 of the frequency f_1 and the

output of the additional sound oscillator 2 of the frequency f_2 are mixed at an appropriate level ratio before entering a switching circuit 3 and the output thus obtained is applied to the tone-color circuit 4.

- 5 The switching circuit 3 is one having a nonlinear characteristic represented for example, by a curved gain, and may exhibit a saturation and a class C amplification as is inherent with such nonlinearly operated devices, a difference sound signal is produced by same having a frequency equal to the difference between f_1 of the fundamental sound signal and f_2 of the additional sound signal. The switched output comprises this difference frequency sound signal, the above described fundamental sound signal, and the additional sound signal, these signals being mixed again and applied to the tone-color circuit 4 so that the natural sound of the triangle can be simulated. FIG. 2 illustrates a circuit diagram of a device simulating the sound of a triangle, which constitutes one embodiment of the present invention. In this circuit, there are provided a fundamental sound oscillator 1 including transistors Tr_1 and Tr_2 ; an additional sound oscillator 2 including transistors Tr_3 and Tr_4 ; a switching circuit 3 including a transistor Tr_5 , a resistor R_3 , and a capacitor C_3 ; and a tone-color circuit 4 including a capacitor C_4 and a resistor R_4 .
- 10 25 The output signals from the oscillators 1 and 2 including a considerable amount of higher harmonics are reduced respectively to appropriate levels through series connected circuits, one of which consists of a resistor R_1 and a capacitor C_1 , and the other of which consists of a resistor R_2 and a capacitor C_2 .
- 20 30 The signals thus reduced to suitable levels are then mixed at the input side of the switching circuit 3. In the switching circuit 3, the mixed signal is then applied to the base electrode of a transistor Tr_5 .
- 35 When a switch S_2 inserted in the emitter circuit of the transistor Tr_5 is opened after it has been closed, the bias voltage of the transistor Tr_5 is varied in accordance with a time constant determined by a resistor R_3 and a capacitor C_3 , whereby the output signal passing through the switching circuit 3 is decayed.
- 40 45 50 At this time, because of the inherent nonlinear characteristic of the switching circuit 3, a difference frequency signal is created, so that as the output of the switching circuit 3, a mixed signal consisting of the above described two signals and the difference frequency signal can be obtained. When the output signal thus mixed is thereafter passed through the tone-color circuit 4 consisting of a resistor R_4 and capacitor C_4 , a desired sound simulating a triangle can be obtained. As a result of various experiments, I have found that, when the frequencies f_1 and f_2 of the fundamental sound and the additional sound are 4 KHz and 1.35 KHz, respectively (difference frequency $f_1-f_2=2.65$ KHz), and the mixing level ratio of the fundamental sound to the additional sound is 1:0.03, a sound creating an extremely natural auditory sensation of a triangle can be obtained. The preferable ranges of the fundamental sound frequency, the additional sound frequency and the mixing level ratio thereof are, respectively, from 3 KHz to 5 KHz, from 1 KHz to 2 KHz and from 1:0.02 to 1:0.04, and the fundamental sound frequency should not be of the just integer multiple of the additional sound frequency.
- 55 60 Although, in the embodiment described hereinbefore, merely a fundamental sound oscillator and an additional sound oscillator are employed, it will be apparent that more than two oscillators may also be employed in the circuit, and when the number of the oscillators are thus increased, a sound producing an even more natural sensation in simulating the sound of a triangle can be obtained.

I claim:

1. A triangle sound simulating device comprising a fundamental sound oscillator for generating a fundamental sound signal, at least one additional sound oscillator for generating an additional sound signal of lower frequency than that of the fundamental sound frequency, the output level of said additional sound signal being lower than the output level of said fundamental sound signal, means to mix said fundamental and

additional sound signals, and switching circuit means of non-linear characteristic which, upon reception of said mixed signals from said fundamental and additional sound oscillators, switches said signals and generates a further sound signal of a frequency equal to the difference between those of said mixed signals at the time of the switching operation, the output of said switching means comprising said fundamental sound signal, said additional sound signal, and said frequency difference signal.

2. A triangle sound simulating device as defined in claim 1 wherein the output signal obtained from said switching circuit is further passed through a tone color circuit.

3. A triangle sound simulating device as defined in claim 1 wherein said switching circuit comprises a transistor and a switching means inserted in the emitter thereof, whereby each time the circuit is switched, a nonlinear characteristic is exhibited in the output of the transistor.
